(57) **CLAIM**

The ornamental design for a barbecue grill top with rotisserie slot, as shown and described.

DESCRIPTION

FIG. 1 is a perspective view showing our new barbecue grill top with rotisserie slot;

FIG. 2 is a left side elevational view thereof, the right side elevational view thereof being a mirror image of that which is shown.

FIG. 3 is a front elevational view thereof;

FIG. 4 is a rear elevational view thereof; and,

FIG. 5 is a top plan view thereof; the bottom plan view is not shown as it does not form part of the claimed invention.
